ROTATING GAME DISK

Morris Gewirtzman, New York, N. Y., assignor to
 The Advertisers' Service Division Incorporated,
 New York, N. Y.

Application May 26, 1944, Serial No. 537,418

2 Claims. (Cl. 273—142)

1

The present invention relates to a game device.

The principal object of the invention is to provide a game of chance which may be made of inexpensive and non-critical materials.

Another object is to provide a game of chance which may be used for advertising purposes.

A further object is the provision of an advertising device which incorporates the features of a game of chance and which may be used as a game of chance.

These objects are attained by mechanism illustrated in the accompanying drawing in which—

Figure 1 is a plan view of the device;

Fig. 2 is a section on the line 2—2 of Figure 1;

Fig. 3 is a section on the line 3—3 of Figure 1;

Figure 4 is a view of the device similar to that of Figure 1 with the top of the casing removed;

Fig. 5 is a fragmentary section on the line 5—5 of Fig. 4;

Fig. 6 is a plan view of the inside surface of the casing of the device, the casing being spread open;

Fig. 7 is a plan view of the ratchet wheel of the device; and

Fig. 8 is a plan view of the pawl and ratchet lever of the device.

The game device herein described, shown and claimed, comprises, as one of its component parts, a casing 10 consisting of a flat sheet of relatively heavy paper or cardboard cut to the pattern shown in Figure 6, folded over on dotted lines 11 and then riveted together as hereinafter described. In the center portion 12 of said casing, approximately in the center of said portion, is an aperture 15. In side flap 14 is another aperture 16 corresponding to aperture 15 in dimensions and registering therewith when flap 14 is folded over upon center portion 12. Above aperture 15 and spaced therefrom is a window 17 of substantially rectangular shape having a small substantially rectangular indentation 18 in its lower edge. Side flap 13 which is oppositely disposed to side flap 14 has, cut into its upper side edge, an angular catch flap 19 shaped somewhat like a boomerang, the lower of its edges 20 being in almost perpendicular relation to said side edge, the other of its edges 21 being in substantially perpendicular relation to its said lower edge 20. The lower edges 22, 23 and 24, respectively, of center portion 12 and side flaps 13 and 14, describe the arc of a circle, edges 23 and 24 coinciding with edge 22 when the side flaps are folded over as aforesaid.

As can be seen in Figure 1 the center portion 55

12, adjacent its lower edge 22, is imprinted with the representation of a dial 25. In the particular embodiment of the invention shown in the drawing, the dial carries a spaced series of descriptive notations, each indicating or representing a different type or method of bombing from the air, thus, high altitude bombing, skip bombing, dive bombing, etc. Adjacent window 17 said center portion carries a picture 26 of a bombardier manipulating a bomb sight and release device said window representing the aperture through which he sights his bombing objective.

A second component part of said game device is the ratchet wheel 30 shown in Figure 7. Like casing 10 ratchet wheel 30 is die cut or otherwise made out of heavy paper or cardboard. It has an axial aperture 31 corresponding in diameter to the casing apertures 15 and 16. The diameter of said ratchet wheel is smaller than either the width or height of center portion 12 of the casing. A dial 32 is imprinted on said ratchet wheel as is shown in Figure 4. In the embodiment of the invention shown in said figure, the dial carries a spaced series of bombing views, each having appended to it, in the same positional relationship to said view as indentation 18 bears to window 17, the word "hit" or the word "miss" according as the particular view shows either a bombing hit or a bombing miss. The teeth of 30 the ratchet wheel are designated by the number 33.

The third component part of the game device is the combination pawl and ratchet lever 40 which like casing 10 and ratchet wheel 30, is made of heavy paper or cardboard. It is cut to the general pattern shown in Figure 8. It is provided with an aperture 41 which corresponds in diameter to that of apertures 15, 16 and 31. A substantially V- or U-shaped slot 42 is cut into 40 said pawl and lever at a spaced distance from said aperture, the vertex thereof pointing in the general direction of said aperture, one of the arms of said slot coinciding with a line passing through said aperture. A finger 43 is formed 45 by and within said slot 42. Side edge 42a formed by said slot opposite said finger constitutes the pawl proper. The projection 44 above said finger comprises a combination ratchet lever and dial indicator. Opposite finger 43 but not necessarily 50 diagonally opposite, is hump 45 whose function will shortly be described.

The edge 46 of hump 45 bears substantially the same angular relationship to edge 47 of ratchet lever 44 that the edge 27 of window 17 bears to edge 28 of V-shaped projection or stop 29 of cas-

ing 10. The distance between aperture 41 and the most distant points 48 of slot 42 is slightly longer than the over-all radius of ratchet wheel 30. The width of finger or pawl 43 at its widest point is equal, substantially, to the width or pitch of ratchet teeth 33.

The game device whose several parts have above been described is assembled in the following manner. The casing 10 is spread out, face down, as shown in Figure 6. The combination pawl and ratchet lever 40 is now placed on center portion 18 of said casing, its aperture 41 registering with casing aperture 15. Ratchet wheel 30 is now positioned on pawl and ratchet lever 40, its aperture 31 in registration with apertures 41 and 15. As it is placed in this position, ratchet wheel 30 is slipped under finger 43. This is shown in Figure 4. Flaps 13 and 14 of casing 10 are now folded over as previously described and flap aperture 16 is now brought into registration with all of the other apertures hereinabove mentioned. Rivet 50 whose shank diameter is such as to provide a fair amount of clearance between it and the edges of said apertures, is now inserted into said apertures and compressed in the usual way leaving, however, sufficient clearance between said casing and said internal parts as to enable said internal parts to rotate in relation to said casing. It should be noted (see Figure 4) that when the flaps are thus folded over upon ratchet wheel 30, the catch flap 19 is slipped under said ratchet wheel in the same manner as said ratchet wheel is slipped under finger 43.

It is apparent that the edge 21a of side flap 13 which lies directly opposite edge 21 of catch flap 19, will engage teeth 33 when ratchet wheel 30 is turned in one direction, and pawl edge 42a which lies opposite finger 43 will engage ratchet wheel teeth 33 when the ratchet wheel is rotated in the opposite direction. It is also apparent that window 17 exposes the bombing scenes of dial 32 and that small indentation 18 exposes the words "hit" and "miss" appearing on said dial.

The game is played as follows: The casing is held in the hand in the position shown in Figure 1. Ratchet lever 44 is moved from the "bombs away" position shown in said figure, to a position opposite any of the dialed notations of bombing styles. As it is thus moved to the left, pawl 42a engages ratchet teeth 33 and causes ratchet wheel 30 to rotate in clockwise direction. Also, as ratchet lever 44 is moved to the left, hump 45 is caused to move in the opposite direction, covering or closing windows 17 and 18. The ratchet lever is now returned to its original position opposite the "bombs away" notation on dial 25. Coincidental movement of ratchet wheel 30 is prevented, however, since edge 21a engages ratchet teeth 33. Windows 17 and 18 are now open and that portion of dial 32 which is found to be exposed is read. If, as is shown in Figure 1, the reading is "hit" the player is credited therewith. If, on the other hand, the reading is "miss," the

player loses to that extent. According to the preferred method of playing this game, the first player to score five "hits" wins the game.

It should be understood that the game device herein described is but a preferred embodiment of the invention. Modifications thereof may be introduced without departing from the essential principles of the invention as hereinafter claimed. Thus the entire device or any part thereof, might be made of other materials than those heretofore described, such as Celluloid, or plastic or metal. Instead of placing bombing style indications on dial 25 and bombing scenes on ratchet wheel dial 32, other notations and scenes might be substituted, such as those of a football or a baseball game.

Advertisements may be carried by said casing 10, as for example in space 51 and on the back of the casing. The present invention is intended to comprise a game device. It is also intended to comprise an advertising device.

I claim:

1. A game device comprising a casing having a window and a catch stop, a ratchet wheel and a pawl carried by said casing on a common pivot, said pawl engaging said ratchet wheel for rotational movement thereof in one direction, said catch stop engaging said ratchet wheel to prevent movement in the opposite direction, an arcuate dial on said casing, a ratchet lever on said pawl movable along said casing dial as an indicator therefor, and a circular dial on said ratchet wheel positioned for exposure through said casing window, the indications on said casing dial having a definite meaning relative to some of the indications on the ratchet dial, the extent of movement of the ratchet wheel and hence of the ratchet dial relative to the casing and the casing dial being determined by, and being at all times proportional to, the extent of movement of the ratchet lever along said casing dial.

2. A game device in accordance with claim 1 in which the casing dial carries a spaced series of descriptive notations, each indicating a different type of bombing operation, and in which the ratchet wheel dial carries a spaced series of descriptive scenes, representing bombing hits and bombing misses, each bombing hit scene having appended to it the word "hit," each bombing miss scene having appended to it the word "miss."
